UNITED STATES PATENT OFFICE.

MAX N. AARON, OF PHILADELPHIA, PENNSYLVANIA.

DESIGN FOR KNITTED TRIMMING FOR UNDERWEAR.

46,105.

Specification for Design.

Patented July 21, 1914.

Application filed May 8, 1914. Serial No. 837,339. Term of patent 7 years.

To all whom it may concern:

Be it known that I, MAX N. AARON, a citizen of the United States, residing in Philadelphia, county of Philadelphia, and State of Pennsylvania, have invented a new, original, and ornamental Design for Knitted Trimming for Underwear, of which the following is a specification, reference being had to the accompanying drawings, which form a part thereof.

The main features of the trimming are the ribbon bar section *a* having the scalloped upper edge in conjunction with the beading or hem stitch effect *b*. The ribbon-bar section comprises a number of spaced-apart "pillar bars" interlaced at the upper edge, by means of a chain thread, with a longitudinally extending thread arranged in a series of bow-shaped or crescent-shaped sections whose outwardly extending members connecting adjacent bows or crescents are located midway between the pillar bars and whose central portions are located in line

with the pillar bars. The lower reversely curved portions of the pillar bars are interlaced, by means of chain threads, with the beading or hem stitch effect, which presents the appearance of a row of rings or loops. Below these rings or loops is a finer open work mesh *c* comprising longitudinal chain threads and fine cross threads. The ribbon bar section affords means to receive a ribbon of normal width while the beading affords means to receive a narrower ribbon if desired.

I claim—

The ornamental design for knitted trimming for underwear, as shown and described.

In testimony of which invention, I have hereunto set my hand, at Philadelphia, on this 5th day of May, A. D. 1914.

MAX N. AARON.
